UNITED STATES PATENT OFFICE.

LOUIS KELLNER, OF BROOKLYN, NEW YORK.

ELECTRIC SWITCH.

1,354,760.

Specification of Letters Patent.

Patented Oct. 5, 1920.

Application filed March 22, 1918. Serial No. 224,059.

To whom it may concern:

Be it known that I, LOUIS KELLNER, a citizen of the United States, and a resident of the borough of Brooklyn, county of Kings, city and State of New York, have invented certain new and useful Improvements in Electric Switches, (Case E,) of which the following is a specification.

This invention relates to improvements in electric switches, and has for its principal object the provision of means for preventing access to live or electrically charged parts of the switch mechanism when the circuit is closed.

Another object of the invention is to provide means whereby it is necessary to operate the switch to break the circuit before access may be had to those parts of the switch through which the current flows when the circuit is closed.

A further object of the invention is to provide a switch mechanism having a casing adapted to inclose the line terminals, fuses, and terminal bridging means, said casing having a cover or door which is positively and automatically held or locked in closed position when the switch is in circuit-closing position and which may be freely opened and closed when the switch is in circuit-breaking position.

Another object of the invention is to provide a switch with a casing inclosing the line terminals, fuses, and movable terminal bridging means, said casing having a door or cover adapted to be automatically closed and held in closed position by means operable by the switch mechanism during the circuit-closing operation of the switch.

Another object of the invention is to provide a switch having movable terminal bridging means, means for automatically locking the terminal bridging means in circuit-closing position, a casing inclosing the line terminals and terminal bridging means and also the fuse or fuses, and means moving with the terminal bridging means adapted to engage a door or cover of said casing and hold or lock said door in closed position when the switch is in circuit closing position and to release said door when the switch is in circuit-breaking position.

In the accompanying drawings, Figure 1 is a vertical longitudinal sectional view of a switch mechanism illustrating the preferred embodiment of the invention, the section being taken on the line I—I of Fig. 2, and the

parts being shown in circuit-closing position;

Fig. 2 a vertical transverse section on the line II—II of Fig. 5;

Fig. 3 a fragmentary horizontal sectional view, parts of the mechanism being omitted to more clearly show the construction of the casing;

Fig. 4 a vertical longitudinal section on the line IV—IV of Fig. 2;

Fig. 5 a horizontal section on the line V—V of Fig. 4; and

Figs. 6 and 7 detail side elevations of parts of the operating mechanism.

The switch shown in the drawings is particularly applicable for use in connection with systems of distribution supplied with high tension currents in which it is the practice to place a fuse in each side of the line adjacent the switch and to provide a switch adapted to make and break the circuit through each side of the line. It will be obvious, however, that the invention may be embodied in various other constructions.

In the preferred construction shown in the drawings, the entire switch mechanism, including the line-terminals, fuses, terminal bridging brushes, switch lever, and the mechanism operated by the switch lever to shift the terminal bridging brushes toward and from circuit-closing position, is mounted within a box-like inclosing case. The inclosing casing comprises a base 1 of porcelain or other suitable non-conducting material, side walls 2, end walls 3, and a cover 4, which is hinged at 5 to one of the end walls 3. The walls 2 and 3 and cover 4 are preferably formed of sheet metal, and the cover 4 may be provided with any suitable form of latch or lock, if desired.

Two vertically extending frame members or plates 6 and 7 are held at their lower ends substantially centrally of the base 1, said members being preferably connected by an integral base plate 8 fastened upon the upper face of the base 1 by suitable screws 9. The frame plates 6 and 7 are connected adjacent their upper ends by a rod 10 on which is rotatably mounted a sleeve 11 having reduced angular end portions 12 and 13. The sleeve 11 is adapted to be oscillated by a swinging switch handle or lever 14 having an angular opening or socket through which the reduced end portion 12 of the sleeve extends. A disk 15 is mounted on the reduced angular end portion 13 of sleeve 11, said

disk being formed with a central angular opening 16 through which said end portion 13 extends to adapt the disk to rotate with said sleeve. The disk 15 is cut away through 5 slightly more than half its periphery to form stop shoulders 17 and 18 adapted to abut against the free end of a pivoted arm or latch 19 when the switch lever is swung to the limit of its throw to break and close 10 the circuit, respectively. The latch 19 is pivotally held at 20 to a lug 21 stamped inwardly from the frame plate 6, and is normally pressed upwardly in the path of the stop shoulders 17 and 18 by a suitable flat 15 spring 22 held to the frame member 6.

A disk 23 is loosely mounted on the rod 10 adjacent the outer face of disk 15, and a mutilated gear wheel or segment 24 is held to the outer face of disk 23 to rotate 20 therewith by means of suitable pins or rivets 25. The teeth of the gear wheel 24 mesh with the teeth of a rack 26 formed at one side of a vertically extending elongated opening 27 in a bracket 29. The bracket 25 or plate 28 is held at its lower end by screws 29, to the upper face of a reciprocable block 30 formed of insulating material. The block 30 and bracket 28 are guided vertically, the block being provided with openings 31 through which the frame plates 6 and 7 extend, and the bracket being provided with an outwardly projecting pin or lug 32 working in an elongated slot 33 formed in the frame plate 7. The pin 32 35 serves also to limit the upward movement of the block 30 and the parts mounted thereon.

A spring 34 is coiled about the sleeve 11 and the opposite ends 35 and 36 of said 40 spring project outwardly at one side of the sleeve in different horizontal planes. The switch lever 14 is provided with an inwardly projecting pin 37 extending between the ends 35 and 36 of spring 34, and the 45 disk 23 is provided with an oppositely projecting pin 38 extending between the ends of said spring. The disk 23 is cut away through slightly more than half its periphery to form stop shoulders 39 and 40 50 adapted to engage latch 19 in the same manner as shoulders 17 and 18 of disk 15, and said disk 23 is also formed with oppositely disposed notches 41 and 42 in which the upper edge of latch 19 is adapted to engage 55 to hold disk 23 against rotation until the latch is released as hereinafter described. The latch 19 is adapted to be disengaged from notch 41 and notch 42 by the inclined or cam-shaped ends 43 and 44 of an arcuate 60 oscillating releasing member 45 pivotally held at 46 to the inner face of disk 15. The disk 15 is provided with two lugs or stop pins 47 and 48 and the arcuate releasing member 45 is adapted to be rocked about 65 its pivot 46 and held against said stop pins

alternately to alternately project the cam ends 43 and 44, respectively, beyond the periphery of the cut-away portion of disk 15 in position to depress latch 19 and disengage said latch from notches 41 and 42 in 70 disk 23, as hereinafter described. The member 45 is adapted to be held against either of the stops 47 and 48 by a flat spring 49 held at one end to disk 15 in any suitable manner and formed with an offset portion 75 50 adapted to engage against opposite sides of a projection 51 formed on the member 45 adjacent the pivot 46 of said member.

Two pairs of spring metal fuse-holding clips 53 and 54 are held to the base 1 in 80 any suitable manner. The clips 53 are electrically connected in the usual manner with line wires forming opposite sides of the circuit, and clips 54 are electrically connected with a pair of stationary terminals or 85 switch contacts 55 held to the base 1. Two fuses 52 of any suitable construction are detachably held in the pairs of clips 53 and 54. A second pair of stationary terminals or switch contacts 56 are held to the base 1 90 opposite the terminals 55, and said terminals 56 are electrically connected in the usual way with line wires forming opposite sides of the circuit.

Two terminal-bridging or circuit-closing 95 brushes 57 are held to the lower side of the reciprocable block 30 by suitable bolts or screws 58, said brushes being preferably countersunk in said block, as shown. The brushes 57 are preferably resilient and 100 formed of a plurality of laminated spring metal plates having downwardly turned yieldable end portions adapted to engage the terminals 55 and 56.

The switch casing is divided horizontally 105 into two compartments, by an intermediate partition or plate 59, held upon suitable angle iron brackets or supports 60, and provided with a hinged section 61 forming a door or cover adapted when open to permit 110 access to the fuses and those parts of the switch through which the current flows when the circuit is closed, such as the brushes and stationary contacts. The door 61 is hinged on a rod 62 which is supported 115 in bearings formed by downwardly bent tongues 63 integral with plate 59. The door 61 is preferably provided with a suitable snap latch 64 having the usual spring 120 pressed and bevel faced bolt 65 adapted to be released by a finger piece 66 working in a slot 67 in the door. The end of bolt 65 is adapted to snap under the adjacent flange of one of the angle brackets 60. The latch 64 serves to normally hold the door 125 61 closed and is especially advantageous when the switch is installed by fixing the base 1 to the side of a wall, as is frequently the case in practice.

The plate 59 is cut away to form a rec- 130

tangular opening 68, one side of which extends parallel with the pivotal point of the hinged cover or door 61. The block 30 carrying the brushes 57 extends through 5 said opening 68 and is adapted to be reciprocated relatively to the plate 59 by the mechanism heretofore described. The reciprocable block 30 is provided with a laterally projecting flange 69, preferably formed integrally therewith and extending laterally from all four sides thereof, as shown. Said flange 69 may, if desired, be formed only on the side of the block 30 adjacent the hinge of door 61, and it will be obvious 10 also that instead of a flange said block 30 may be provided with any suitable form of projecting device adapted to engage the outer side of door 61. The flange 69 is adapted to seal the edges of opening 68 15 when the switch is in circuit-closing position to prevent any possibility of accidentally or otherwise establishing electrical contact between the body of a person and live parts of the switch through said aperture. It will 20 be observed also that a portion of said flange 69 extends beyond the hinge rod 62 and overhangs the door or cover 61. The flange 69 is so positioned that it closely engages the outer face of plate 59 and door 61 when 25 the switch is in circuit-closing position, thus not only sealing opening 68, but also positively engaging the outer face of door 61 and holding said door in closed position against the brackets 60. As the block 30 is 30 automatically locked in its inner or circuit-closing position by latch 19, disk 23, pinion 24, and rack 26, it will be seen that the door 61 is positively locked or held against opening movement by the act of operating the 35 switch to close the circuit, said locking means moving with the movable contacts or terminal bridging brushes 57 to lock and release said door 61 when the switch is in circuit closing and breaking positions, respectively. 40

The construction and operation of the mechanism heretofore described for reciprocating and locking block 30 and the contact brushes 57 is the same as that shown and described in my copending application Serial No. 205,139, filed December 3, 1917. To close the circuit, the lever 14 is swung through an arc of substantially 180° from the position shown in Figs. 2, 4 and 5, to the 45 position shown in Fig. 1. It will be observed that, as lever 14 is thrown over, the sleeve 11 and disk 15 are rotated in a clockwise direction while disk 23 is held stationary by latch 19, which is held engaged in notch 41 in disk 23 by spring 22. It will also be seen that spring 34 is wound or placed under tension by pin 37 on lever 14 which forces the end 35 of said spring 34 before it as the lever is swung to the right. When 50 lever 14 is in the position shown in Figs.

4 and 5 the cam end 44 of releasing member 45 is in projected position with its rear face 44a in position to engage latch 19 during the initial movement of the switch handle. As the rear face 44a of cam end 44 of member 45 rides over latch 19 said member 45 is rocked about its pivot 46, as spring 22 is stronger than spring 49, thus forcing the projection 51 to the opposite side of projection 50 on spring 49, thus retracting cam end 44 and projecting cam end 43 of releasing member 45 beyond the periphery of disk 15 in position to engage and depress latch 19 when the handle or lever 14 approaches the limit of its throw. 55

As lever 14 approaches the limit of its throw the inclined end 43 of member 45 engages latch 19 and depresses said latch, thus releasing disk 23 which is rapidly rotated in a clockwise direction by reason of the engagement of the end 36 of spring 34 under pin 38 on disk 23. The rapid rotary movement of disk 23 imparts a similar rapid semi-revolution to mutilated gear 24 which meshes with rack 26. It will be seen, 60 therefore, that rack 23 and bracket 28 will be projected with a snap action toward base 1, carrying block 30 and brushes 57 to the position shown in Fig. 1, in which position the ends of brushes 57 engage the two pairs 65 of contacts or fixed terminals 55 and 56 and close the circuit. As soon as disk 23 completes its semi-revolution to force the brushes 57 into firm and close engagement with contacts 55 and 56, the latch 19 will 70 snap into notch 42 in disk 23 and positively lock said disk and the gear 24 against rotation, thus also locking rack 26 and block 30 in their inner or circuit-closing positions. The circuit-breaking operation is the reverse of the operation just described. 75

It will be observed that the block 30 is thus automatically locked in its inner or circuit-closing position and also in its circuit-breaking position, and that said block 80 carries means adapted to engage door 61 and hold said door locked in closed position when the switch is operated to close the circuit and to release said door to permit opening thereof when the switch is operated to 85 break the circuit. It will be further observed that if door 61 is open when the switch is operated to close the circuit, the flange 69 will engage and close said door and positively lock the door when the switch 90 mechanism moves to circuit-closing position. It will be obvious also that the cover 4 and all that part of the casing above plate 59 and door 61 may be dispensed with, if desired. 95

What I claim is:

1. In an electric switch, the combination of an operating handle, movable terminal bridging means, line terminals, means for automatically locking the bridging means in 100

- “on” and “off” positions, means controlled by movement of said handle a predetermined extent for temporarily releasing said locking means and shifting the bridging 5 means, a casing inclosing the bridging means and line terminals, a movable closure for said casing, and means located exteriorly of said casing movable with the terminal bridging means into engagement with said closure 10 when the bridging means is shifted to “on” position to prevent opening of the closure without first shifting the bridging means to “off” position by an operation of the handle.
2. In an electric switch, the combination 15 of line terminals, terminal bridging means, a reciprocable support for said bridging means, a casing inclosing the live parts of the switch and having an opening through which said support is reciprocated, a hinged 20 closure for the casing having one edge located adjacent said opening, an operating handle, means controlled by the handle for reciprocating the support and automatically locking the support in its shifted positions, 25 and an abutment on said support adapted to engage the outer side of said hinged closure when the support is locked with the bridging means in circuit-closing position.
3. In an electric switch, the combination 30 of line terminals, fuse terminals, a casing inclosing the line terminals and fuse terminals, a door for the casing, terminal bridging means within the casing, means recipro-
- cable through an aperture in the casing for operating the bridging means, an operating handle, means operable by movement of the handle a predetermined extent for actuating said reciprocable means and positively locking said reciprocable means against movement except by the handle, and means carried by said reciprocable means movable into engagement with the outer side of the door when the bridging means is shifted to circuit-closing position.
4. In an electric switch, the combination 45 of line terminals, terminal bridging means, a casing inclosing the line terminals and bridging means and having an opening therethrough, a support for the bridging means reciprocable in said opening and having a laterally extending flange overhanging the edges of said opening, a closure for the casing hinged at one edge adjacent said opening, and an operating handle located exteriorly of the casing for reciprocating 50 said support to make and break the circuit and to shift said flange on the support into and out of engagement with the outer side of the closure and the outer side of the casing around the edge of the opening therein 55 to seal said opening and hold said closure in closed position when the circuit is closed.

In testimony whereof I hereunto affix my signature.

LOUIS KELLNER.
